AUTOMATIC PAINTING MACHINE

Robert B. Way, 1437 Chelsea Ave., and Carl D. Hersey,
3107 Marvin Ave., both of Erie, Pa.
Filed May 1, 1958, Ser. No. 732,350
3 Claims. (Cl. 118—301)

This invention relates to processing machines and, more particularly, to machines for automatically painting articles of manufacture wherein the processing tool or paint gun and the work move relative to each other in a parallel path.

The machine described herein has especial utility in the field of automatically painting predetermined areas on articles of manufacture such as plastic parts and the like.

In previous machines, particularly painting machines, for painting articles of manufacture wherein the paint applying means and the work moved relative to each other, these machines had the disadvantage that the relative movement of the work and the paint applying means was not constant and where mechanisms were provided for making the said relative movement constant, the mechanisms were complicated and not compact in arrangement. In many cases, the relative movement between the work and the tool was not smooth and, therefore, the coating material was not applied to the articles of manufacture in a smooth even manner. Further, on previous machines of this type, it was difficult to mount the coating applying means in such a way that the coating could be applied in the desired manner to the work and the tools could not generally be spaced laterally a sufficient distance from each other.

In the machine disclosed herein, by using the rotomotion motor, the chain drives achieve a very smooth travel of the guns due to the fact that hydraulic oil is used in the driving means. The speed of the carriage is entirely constant; that is, there is no change in the velocity of the carriage as there would be when a crank and a lever arm are used for driving a reciprocating mechanism and a variable stroke is used on the carriage. Valves are mounted together on a movable bracket which can be moved clockwise around the cam, thus shortening the length of stroke. The stroke then can be cut down to almost six or eight inches if there is a short part to be painted.

The crankshaft on which the guns are mounted is fashioned in such a way that it can hold one, two, or up to as many as four spray guns. It can spray one color out of one pair of guns and another color out of the other pair.

Another feature of the machine is the adjustable fixture which holds the part for painting. This fixture can be positioned in such a manner that the part can be held under the center of the carriage or it can be held to the front or the back of the carriage. A gun cannot be mounted directly in the middle of the carriage but, by moving the fixture, the part can be placed directly under a gun which sits on the front of the crank of the crankshaft and, therefore, it is possible to paint straight down on the machine. The length of the cam shaft permits mounting of the guns spraying down at angles so that complete coverage of the part is accomplished. The tilting of the guns, of course, permits painting around bridges and into corners and otherwise inaccessible places and the mounting of the guns spraying in from the side also helps in that way. A depressed part or a raised part can be painted and very good coverage can be obtained because the spread of the guns on the crankshaft is also aided by the bend of the tilting mechanism. Some previous machines of this description have utilized a hydraulic cylinder which extended beyond the side of the

2

machine because of its extreme length. The machine will be twice as long as the cylinder.

More specifically, it is an object of this invention to provide a machine which will accomplish the purposes set forth herein and, more particularly, it is an object to provide a machine which is simple in construction, economical to manufacture, and simple and efficient in operation.

Another object of the invention is to provide a machine for the purpose set forth wherein the work and the processing tool move relative to each other in a longitudinal path, the movement being smooth and constant.

Still another object of this invention is to provide an improved fixture in combination with an automatic painting machine.

A further object of the invention is to provide an improved means for supporting a paint gun on an automatic painting machine.

Yet a further object of the invention is to provide an improved automatic painting machine.

With the above and other objects in view, the present invention consists of the combination and arrangement of parts hereinafter more fully described, illustrated in the accompanying drawings and more particularly pointed out in the append claims, it being understood that changes may be made in the form, size, proportions, and minor details of construction without departing from the spirit or sacrificing any of the advantages of the invention.

30 In the drawings:

FIG. 1 is an isometric view of the machine disclosed herein to a reduced scale;

FIG. 2 is a partial view of the overhead operating mechanism for the machine with certain parts omitted;

FIG. 3 is a top view of the driving mechanism shown in FIG. 2 with certain parts omitted;

FIG. 4 is an end view of the mechanism shown in FIGS. 2 and 3 with certain parts omitted;

FIG. 5 is a partial view of the gun tilting mechanism 40 according to the invention;

FIG. 6 is a side view of the mechanism shown in FIG. 5; and

FIG. 7 is a piping diagram of the machine according to the invention.

Now with more specific reference to the drawings, the machine is made up of a frame 100 having four spaced legs 101 which support a top frame member 102. On the top frame member 102 is supported an overhead reciprocating mechanism 103 which includes a rotomotion motor 104 and a gun carriage 113 having a gun tilting mechanism 83 thereon. The motor 104 has a mounting plate 105 fixed thereto and has a slot 115 formed therein. The slot 115 receives a sliding bracket 112 which supports valves 18 and 23. The rotomotion motor can be constructed like the motor shown in Patent No. 2,793,623 or Patent No. 2,798,462.

The valves 18 and 23 are connected together so that they slide in unison with the sliding bracket 112. Valves 17 and 28 are fixedly attached to the plate 105. A handle 117 extends through the bracket 112 and through the slot 115 and is threaded into a nut plate 124. When the handle 117 is rotated to loosen it in the nut plate 124, the bracket 112 may be slid along the slot 115 in the mounting plate 105, thus adjusting the position of the valves 18 and 23 and thereby adjusting the stroke of the gun carriage 113.

Cover members 106 may constitute the top of a table and the cover members 106 are flat on top and supported on laterally disposed channel members 107 and 108 which have angle members 109 attached to the lower ends thereof. Tracks in the form of longitudinally disposed rods 110 extend through holes in the vertical flange

of the angle members 109 and have nuts 111 thereon which secure the rods 110 in place whereby they are supported.

The gun carriage 113 is made up of two blocks 135 and 133 held together by two I-frame members 116 which are connected by a plate 139. Bores through the blocks 135 and 133 receive the track rods 110 and slide thereon. A plate 114 is attached to the inner side of the block 133. A cylinder 21 is attached to the front end of the plate 114 by means of screws 136 and a cylinder 22 is attached to the other end of the plate 114 by means of screws 137.

A longitudinally extending plate 137' is attached to the lower side of each block 133 and 135 and to each plate 137' is attached one of the pillow blocks 138. An intermediate bearing 139 of a crank 85 is journalled in the pillow blocks 138 and crank arms 140 and 141 support gun supporting arms 142 and 143. An intermediate block 83 is clamped to the intermediate bearing 139 by a bolt 144. A block 83' has an arm 145 attached thereto and the arm 145 has a vertical slot 146 therein.

The piston rods of the pistons in the cylinders 21 and 22 are integrally attached together and a laterally extending pin 147 is fixed to a rod 77 and extends radially therefrom and is received in the slot 146 in the arm 145. Since the bearing 139 is journalled in the blocks 138, it cannot move but can only rotate and as the piston rod 77 moves from side to side, the arm 145 rotates the bearing 139 and swings the arms 142 and 143.

The top plate 130 is attached to plates 118 which are attached to a chain 119. The chain 119 passes around sprockets 120 and 121 and around a sprocket 122 which is attached to a shaft 123' of the rotomation motor 104. The sprockets 120 and 121 are supported on shafts 150 and 151 which are journalled in pillow block bearings 123 which are, in turn, fixed to the cover members 106 of the frame 100.

As the rotomation motor 104 rotates, its sprocket 122 rotates with it and this drives the chain 119, thereby causing the carriage 113 to traverse on the rod tracks 110. The plates 118 are held in place by screws 149 and may be moved to adjust the tension of the chain 119. The rotomation motor 104 is constructed such that when oil is forced therethrough in one direction, the motor 104 rotates in a first direction and when the oil is forced through it in a second direction, the motor 104 rotates in the opposite direction. Therefore, when oil is forced through the motor 104 in one direction, it will move the gun carriage 113 to the right and when the oil flow is reversed, it will move the gun carriage 113 to the left.

A rest pad 129 is attached to the upper end of a square piston rod 126 for supporting a part 131 to be painted. The piston rod 126 is square in cross section to prevent it from rotating during its upward and downward travel.

A mask 132 is generally rectangular in shape and its ends are received in slots 134 in rods 148. The rods 148 are fixed to support members 152 which are in turn fixed to base plates 153 in turn fixed to a plate 154. The plate 154 is fixed to a lower frame member 159. The lower frame members 159 are fixed to the legs 101.

When air is applied in a cylinder 125 below a piston 127, the piston rod 126 will raise the rest pad 129 and the part 131 to bring the part 131 into a concavity located in the central portion of the mask 132. The said concavity will be in the form of a counterpart of the surface of the part to be painted with openings therethrough to allow paint from guns 162 to be deposited on the exposed areas of the part. The mask 132 is of the type in general use with automatic painting machinery.

Air and Hydraulic Circuit

The air and hydraulic circuit is shown in FIG. 7 and shows a cam 16 which is attached to the shaft 123' of the rotomation motor 104. The oil circuit for the rotomation motor 104 is made up of pipes 30, 31, and 32 and a

pump 33 which is driven at a constant rate of speed. The flow of oil through the pipes 30, 31, and 32 is controlled by valves 14 and 25 as well as restricting check valves 35 and 36 which each allow oil to flow freely in one direction but check the flow thereof in the other direction and meter the flow, thereby checking the movement of the motor 104. The pump 33 is supplied fluid from a sump 39 and the pump 33 discharges fluid through the valves 25 and 14 to the rotomation motor 104.

Air is supplied through a line 40 at a suitable pressure and it flows through a filter 41 and to a pipe 42. From the pipe 42, it flows through a pressure regulator 43 to a line 44 at a predetermined pressure to the atomizing air supply on the guns 162. This pressure may be observed on a gauge 45. Air from the filter 41 further passes through a lubricator 53 into a line 54 which is the main air supply line to the machine.

Air from the pipe 42 is also connected to the main air passage of a starting valve 46 which is a manually controlled valve having a manual control 47 thereon which may be operated either by the hand or by the foot of an operator and which controls the flow of air either to a control line 48 and thence to a cut-out valve 49 or to a line 50 which is connected to a pilot control 51 of a valve 26. The line 50 exhausts through an exhaust 52 when the manually controlled valve 46 is turned off.

Starting the Machine

With the machine disclosed herein, the cut-out valve 49 will pass through so much air and then shut off. There is air going through the starting valve 46 through the line 48 to the cut-out valve 49 and the air cannot pass through the cut-out valve 49 until the pressure behind it is discharged and air pressure is again put on it. Therefore, to start the machine, the operator actuates the starting valve 46 which may be a foot pedal or a hand actuated spring return four-way valve. This exhausts the line 48 and exhausts the cut-out valve 49. At the same time, air flows from the pipe 42 through the valve 46 and the line 50 to the pilot control 51 of the valve 26. The pilot control 51 opens the valve 26, passing air from a regulator 167 and a line 97 through a line 98, check valve 99, the orifice in parallel with valve 99', and pipe 164 to the cylinder 125 which raises the piston 127, forcing the part 131 to be painted into the mask 132.

When the starting control valve 46 is released, a spring 61 reverses it and it comes back to the position shown. Thus, when the valve 46 is actuated, it allows air to pass first through the line 50 to the pilot control 51 connecting air to a pipe 164 and then through the valve 46, the line 48, through the cut-out valve 49, a line 60, to a double pilot operated three-way valve 11. This air pressure will be impressed on a pilot 12.

No time delay in the air circuit is necessary between the actuation of the cylinder 125 and the actuation of the guns 162. The amount of time required to press the foot pedal down, let it up, and the machine to start is enough for the air piston 127 to completely push the part 131 into place in the mask 132 before the gun 162 starts to move so there is no positive mechanical linkage necessary to delay the starting of the gun carriage 113. Flow control valve 16' is used to delay the opening of the spray guns 162 so as to insure that the guns 162 do not start to spray before the carriage 113 starts to move. Actuating the foot pedal will raise the air piston 127, pushing the part 131 into the mask 132 and also exhausting the cut-out valve 49. When the foot pedal is released, the cut-out valve 49 will, of course, pass air to the valve 11. The piston 127 does not drop when the foot pedal is released because the valve 26 which controls it is a double piloted valve and it remains open until it is closed by air from the valve 17 as a cam 16 rotating clockwise engages it. When air from the valve 17, closes the valve 26, the air under the piston in cylinder 125 flows back through check valve 99', through the orifice in parallel with valve

99, and is exhausted into the atmosphere by valve 26. Thus, the piston in cylinder 125 descends at a rate controlled by the size of the orifice in parallel with check valve 99.

The air coming in from the starting valve 46 through the cut-out valve 49 will move the control member in the valve 11, opening the valve 11. This puts air pressure in a line 13 and the air flows through the line 13 to the left over a pilot 62 of a left hand hydraulic valve 14 and opens the valve 14. Air from the line 13 also flows to a pilot 63 on a three-way valve 15. When the valve 15 is thus opened, air flows therethrough from a line 54 through a line 64 and a valve 20 to a line 65, a shut-off valve 66, a quick exhaust valve 67 to a line 68, and thence to the spray guns 162. The hydraulic valve 14 which has been opened by the pilot 62 passes hydraulic fluid from a pipe 32 to a pipe 30 and thence to the rotomotion motor 104 which starts the cam 16 rotating counterclockwise.

The first portion of rotation of the cam 16 to the valve 17 is not effective on counterclockwise rotation as the valve 17 operates only when the timing cam 16 is rotating clockwise. The valve 18 operates only when the cam 16 is turning counterclockwise and does not operate when the cam 16 is rotating clockwise. Therefore, the valve 14, having opened, will pass oil to the rotomotion motor 104 and the cam 16 will be rotated counterclockwise. Since the shaft 123' is also connected to the sprocket 122, the gun carriage 113 will move to the right.

This movement will continue past the valve 17 not affected until a cam surface 70 strikes an actuating member 71 on the valve 18. This will open the valve 18, passing air from the valve 18 and the line 54 to a line 72 and a four-way valve 19. This will actuate a member 84 on the valve 19 and connect air from the line 54 to a line 74 which operates the gun tilting mechanism through a flow control valve 56 and the cylinder 21 having a piston 76 therein connected to the piston rod 77. Air also flows from the line 72 to the gun shut-off valve 20 which is closed, thus shutting off the spray guns 162. The cam surface 70 is just before the end of the stroke so that as the gun carriage 113 reaches a point near the end of its travel toward the right, the piston rod 77 will act through a pin 147, the block 83, and a crank 140 to incline the guns 162 and cause them to direct their spray in the other direction. The guns 162 will be shut off just before they start to tilt.

Rotation of Cam 16 (From Valve 18 to Valve 23)

The cam 16 continues its rotation until the surface 70 strikes actuating member 86 on the three-way valve 23 at the end of the stroke of the cam 16. When the valve 23 is opened, air is passed from the line 54 to line 87 and then to a pilot 12' of the valve 11, pilot 89 of the valve 24, and pilot 90 of the valve 20. The valve 11 is thus closed, exhausting pilot 62 of the valve 14 and pilot 63 of the valve 15.

Pressure on the pilot 89 of the valve 24 opens the valve 24, passing air from line 54 to line 91 to pilot 161 of the valve 25 and the pilot 160 of the valve 14. This action closes the valve 14 and opens the valve 25 which causes the rotomotion motor 104 to reverse its motion to a clockwise rotation. The passage of air to the pilot 90 of the valve 20 opens the valve 20, permitting actuating air to flow from the line 54 through the valve 15, the line 64, the valve 20, the line 65, the shut-off valve 66, quick exhaust valve 67, and line 68 to the spray guns 162, turning them on to spray as the carriage 113 moves to the left.

The valve 25 is opened, the valve 14 is closed, and the motor 104 is reversed and the motor 104 now rotates clockwise, thus moving the carriage 113 to the left. The guns 162 have been turned on when the valve 20 is opened and the tilting mechanism is tilted so that the guns 162 now spray and are inclined in the opposite di-

rection and the spray will continue as the cam 16 rotates clockwise past the valve 18 which is not effected by clockwise rotation of the cam 16. When the cam 16 opens the valve 17, the air from the line 54 flows therethrough to the line 94 to pilots 95 and 96 of the valves 15 and 26. The valve 15 shuts off the spray guns 162 and the three-way valve 26 connects the line 98 to the exhaust port, exhausting line 164 and the air cylinder 125. The piston rod 126 of the cylinder 125 which has been holding the part being painted tightly in the mask is thus lowered, dropping the part down out of the mask.

The cam 16 continues to rotate past the valve 17 until the surface 70 engages member 163 on the valve 28. Air from the line 74 through the valve 28 flows to pilot 155 of the valve 25 from line 156 and closes the valve 25, thus stopping the rotomotion motor 104. Air from the line 156 also actuates pilot 157 on the valve 19. When air is applied to the pilot 157 of the valve 19, it reverses the air flow through the valve 19, applying air to line 81 and to the air cylinder 22. This moves the piston rod 77 to the left and tilts the gun holding mechanism, including crank 85. The air in the line 156 also flows to the pilot 158 of the valve 24 and closes the valve 24.

As the air in the line 74 which passes through the valve 28 is supplied through the valve 19, the valve 28 actually shuts off its own air supply when it opens and allows air to flow to the pilot 157 of the valve 19. Therefore, restrictor 170 has been placed in the exhaust port of the valve 19 so that sufficient pressure will be momentarily retained in the lines 74 and 156 to ensure the actuation of the pilots 158, 155, and 157.

Valve 180 is installed in the circuit as a safety feature. It is a manually operated valve having a manually actuated member 181 which, when actuated, connects air from the line 54 through check valve 165 to pilot 96 of the valve 26. Air on the pilot 96 will close the valve 26, thus exhausting line 98 and line 164. Gravity will then lower the piston rod 126 and drop the part 131 down out of the mask 132.

The manually operated valve 128 may be used to test or clean the spray guns 162 when the machine is at rest. Flow control valves 35 and 36 control the flow of oil from the rotomotion motor 104 and are used to adjust the speed of the gun carriage 113. Flow control valves 177' and 56 are used to adjust the speed with which the guns 162 are tilted at the end of each stroke. Flow control valves 99 and 99' are used to control the ascent and descent of the piston rod 126 of the cylinder 125.

The foregoing specification sets forth the invention in its preferred practical forms but the structure shown is capable of modification within a range of equivalents without departing from the invention which is to be understood is broadly novel as is commensurate with the appended claims.

The embodiments of the invention in which an exclusive property or privilege is claimed are defined as follows:

1. A machine for painting articles of manufacture comprising a frame, track means on said frame, a carriage on said track means reciprocable thereon, a motor and a paint gun on said carriage, liquid means driving said motor, said motor driving said carriage and the gun thereon smoothly at a constant velocity, a paint mask mounted on said frame, means to stop said motor and to reverse the movement thereof on said track means, said carriage moving with said gun thereon in proximity to said mask to spray paint thereon, air means to actuate said liquid means and said gun to spray paint on said mask while said carriage is moving, and means to stop the spraying of said gun before the movement of said carriage is stopped.

2. An automatic painting machine comprising a frame, an article support on said frame adapted to support an article, a paint dispensing means supported on said frame for reciprocation thereon to deposit paint on said article, means to actuate said dispensing means to spray paint on

said article adapted to be supported on said article support, a liquid motor on said frame to reciprocate said paint dispensing means and liquid means for applying power directly to said liquid motor, and air means controlling the liquid for said liquid motor.

3. An automatic painting machine comprising a horizontally disposed track, a gun carriage reciprocably supported on said track, a laterally disposed crankshaft having a paint gun on its distal end supported on said gun carriage, an air actuated cylinder having a piston rod therein attached to said crankshaft, a reversible hydraulic motor on said machine, spaced sprockets, one disposed on said machine at each end of said track, a sprocket on said motor, a chain passing around said sprockets and attached to said carriage, said motor driving said sprocket thereon to move said carriage on said track, said carriage movable from a first end to a second end and return on said track in a cycle, a cam driven by said motor, valve means controlling the flow of liquid to said motor to control the direction of rotation thereof, a first, a second, a third, and a fourth air control valve on said machine actuated by said cam, said first valve being actuated upon rotation of said motor in a second direction and said second valve actuated upon rotation in a first

direction, said second valve actuating means to actuate said air cylinder to rotate said crankshaft to tilt said gun in a reverse direction and actuating means to stop said paint gun from spraying, said third valve actuating means to reverse said motor at the end of movement of said carriage in a first direction by closing said valve means controlling the flow of liquid, said first valve actuating means stopping the spraying of said gun near the end of travel in a second direction, said third valve also actuating means starting said gun to spray at the start of travel of said carriage in a second direction, and said fourth valve actuating means stopping said motor at the end of a cycle of movement of said carriage.
